Attorney

UNITED STATES PATENT OFFICE.

THOMAS A. VITALLO, OF SCHENECTADY, NEW YORK.

REGISTER FOR BARBER SHOPS, ETC.

Application filed October 20, 1921. Serial No. 509,125.

To all whom it may concern:

Be it known that I, THOMAS A. VITALLO, a citizen of the United States, residing at Schenectady, in the county of Schenectady 5 and State of New York, have invented certain new and useful Improvements in Registers for Barber Shops, Etc., of which the following is a specification.

This invention relates to recording devices, and more specifically to an improved register for barber shops and similar places of business where customers, patients, etc., have to wait their respective turns.

One object of the invention is to provide an improved, comparatively simple and inexpensive, and thoroughly practical device for visually dividing a strip of paper into a series of cards, each card being, a convenient size and shape to receive only a single signature.

A further object of the invention is to provide a device of this character with a simple and very effective means for holding a roll of paper in position to feed an unwound portion thereof through a passage which comprises a platen, at one side, and a grating at the opposite side; this grating constituting the means for visually dividing the paper into name cards; the invention also including a simple and effective means for severing the cards, one by one, as the customers or patients arrive or retire.

A further object is to provide a device of this character in which the platen and grating are hinged to one another in such manner that fresh rolls of paper can be quickly, easily and conventionally applied in position for use.

Other objects and advantages will be pointed out or implied in the following details of description in connection with the accompanying drawings in which:

Figure 1 is a front elevation;

Figure 2 is a vertical sectional view;

Figure 3 is a horizontal sectional view along the line 3—3 of Figure 1.

Referring to these drawings in detail, in which similar reference characters correspond to similar parts throughout the several views, and in which a roll of writing paper is indicated at 5, the invention consists of the construction and arrangement of parts, in connection with the roll of

paper, as will now be specifically pointed out.

A platen 6 has a grating 7 hinged thereto at 8, this grating or frame comprising a series of spaced, parallel and horizontal bars 9 which are also spaced from the platen 6 a slight distance which is sufficient to provide a passage through which the unwinding end of the strip of paper 5 is caused to pass by the owner pulling its extreme lower or forward end beyond the end of the passage, as illustrated. The platen or frame or both may be provided with a cutting edge 7^a against which the paper may be pulled laterally for severing the free card 5^a from the confined cards 5^b, 70 that is, the cards which remain in the passage between the platen and grating after the card 5^a has been extended to the position shown.

The grating 7 is provided with spring clips 10 which engage with the opposite edge of the platen 6 from the hinge 8. These clips normally hold the platen and grating in position for forming the paper-passage, but when they are disengaged from the platen, the grating can be swung on the hinge 8, and the unwound portion of a roll of paper can be placed against the platen while the wound portion is passed axially into the cylinder 11 which constitutes a 85 holder for the paper-roll. This cylinder is provided with a closure 12 which is removable for permitting the paper-roll to thus be inserted, and is also provided with an axially parallel slot 13 which communicates with the paper-passage.

According to the present disclosure of my invention, the roll holder 11 is united with the frame or grating 7, but it is not beyond the scope of this invention to otherwise support the roll holder at one end of the passage. Moreover, it is not intended to limit this invention to the exact details of construction and arrangement shown and specified, but changes may be made within the 100 scope of the inventive idea as implied and claimed.

What I claim as my invention is:

The combination of a platen, a frame secured to one edge of the platen and normally extending thereacross in spaced relations thereto to provide a passage, a cylinder on one end of said frame and having

an axially parallel slot normally in communication with said passage, said cylinder receiving a roll of paper which frictionally engages with the bottom of the cylinder to retard the feeding of the paper through said passage, said frame including a series of bars sufficiently spaced from one another to provide openings through which persons

can write their names on the paper against said platen, and means, at the opposite end 10 of the frame from said cylinder, to sever the paper that bears one name from the paper that bears other names.

In testimony whereof, I, affix my signature.

THOMAS A. VITALLO.
